AUTOMATIC FLUSHING APPARATUS FOR WATER CLOSETS AND LIKE PURPOSES

Pierre Emile Vuagnat, Paris, France

Application September 18, 1935, Serial No. 41,139
In France September 22, 1934

2 Claims.

(Cl. 4-28)

The present invention relates to an improvement in apparatus for flushing water closets and for similar purposes of the type (hereinafter referred to as the type specified) comprising a hermetically closed reservoir having an opening for the discharge of the flushing water which is normally closed by a piston valve arranged to slide in a cylinder that communicates, at the lower end, with the interior of the reservoir and, at the upper end, with a low pressure tube by way of an opening controlled by an auxiliary valve adapted to be actuated by the device for initiating the flushing operation.

The particular advantage of apparatus of this type is their ease of use due to the fact that they do not necessitate more than a very weak initiating effort in order to produce the lowering of pressure which, by destroying the equilibrium of the pressures within the reservoir, automatically causes the raising of the flushing valve, in contradistinction to those apparatus where the flushing valve is actuated directly by the user who must exert a stronger effort in order to overcome the pressure of the water and compressed air which is acting on this valve. However, in the apparatus of the type specified the disposition of the low pressure tube and of the control members for initiating the flushing operation presents certain practical difficulties which are evidenced by an increase in the size of the apparatus and in the costs of construction and installation. On the other hand the control members and the members for initiating the flushing operation are only accessible with difficulty which renders the upkeep of these apparatus relatively difficult.

The present invention obviates the difficulties set out above due to the fact that, in an apparatus of the type specified, the cylinder for the piston valve and the low pressure tube are formed as two adjacent compartments in a single casting which is mounted on the bottom of the flushing reservoir to constitute together with the said bottom and the device for initiating the flushing operation, which is also supported by the said bottom, a compact unit detachable from the reservoir.

This particular disposition of the low pressure tube and of the control members results in a simplification of the construction of the apparatus and a reduction in its size. The mounting and dismounting of the accessories unit may be effected very rapidly and this facilitates the upkeep of the apparatus.

In the accompanying drawing there is shown,

by way of example, one way in which the invention may be carried into effect.

In the single figure of this drawing, showing a longitudinal section of the apparatus according to the invention, the flushing device comprises a tank 101 connected to a supply 102 of water under pressure; at its lower part, above the outlet pipe 103, is disposed a cylinder 104 containing a piston valve 105, the lower spherical part 106 of which is adapted to cooperate with the rubber seat 107; at the upper part of the cylinder 104 there is provided a chamber 108 having its upper side formed with a calibrated aperture 109; this chamber communicates with a low pressure pipe 110 opening at 111 into the outlet pipe 103 and forming with the adjacent cylinder 104 a single cast piece supported by the tank bottom 101'; at the mouth of this pipe 110 there is a rubber ball valve 112 secured on a rod 113, the lower part 114 of which passes through a packing 115 and is pulled downwards by a spring 116 resting upon the head 117 of the rod; an operating handle 118, pivoted on an axis 119 carried in two eyes 120 formed on the extension 101'' of the tank bottom 101', is provided with a lug 121 at right angles, capable of lifting the rod 113 of the ball valve 112 when the handle 118 is depressed.

In the tank 101 is disposed a pipe 122 for the evacuation of the air, said pipe opening in the tank at its upper end 123 and into the atmosphere, at 124, by its lower end. On this tube 122 is disposed a small chamber 125, provided at its lower part with a seat 126 and containing a light ball 127. It will be seen that, upon filling of the tank, as soon as the air tends to escape, the valve 127 will close.

The operation of the device described is as follows: The piston valve 105 having been lifted (as will be explained further) and all the water contained in the tank having been emptied by the outlet pipe 103, the piston valve 105 falls back upon its seat due to its own weight, the tank is filled by the supply pipe 102 under pressure and the ball valve 127 of the air pipe 122 falls immediately back upon its seat 126 and prevents the exit of the air. The level of the water rises up to 128, retaining at the upper part of the tank all the air included in the latter, the air being compressed to the pressure obtained in the pipe 102, for instance to 3 kg./cm². The upper chamber 108 of cylinder 104 is now filled with water.

If it is desired to effect another flushing operation, it is merely necessary to destroy the equi-

librium of the pressures in the tank 101 by putting the cylinder 104 into communication with the opening 111 by way of the low pressure pipe 110. This communication is set up by the depression of the handle 118 whereby the ball valve 112 is lifted from its seat to permit of the sudden emptying of the water from the chamber 108 through the passage 111 and the outlet pipe 103. The piston valve 105, which is no longer subjected to pressure on its upper surface, is lifted from its seat 107 by the water pressure acting upwards through the two large apertures 104 formed in the lower part of the cylinder 104, thus putting the interior of this cylinder and the outlet pipe 103 into direct communication with the interior of the tank 101. All the water contained in the latter is expelled into the pipe 103 by the expansion of the air under pressure at the upper part of the tank. At the end of this phase, the losses of air which may be due to the solution of the air under pressure, in the water, or otherwise, are compensated by an arrival of air from the outside through the tube 122, thereby lifting the ball valve 127. The piston valve 105 falls back upon its seat, the tank fills up through the pipe 102, and the water, the level of which rises, penetrates into the upper chamber 108 of the cylinder 104 and expels the air which has been introduced into the latter during the emptying of the tank. The flushing device is again ready for operation.

I claim:

1. Apparatus for flushing water closets and for similar purposes comprising a hermetically closed reservoir, a supply of water under pressure at

the upper part of the reservoir, an outlet pipe at the lower part of the reservoir, a detachable bottom at the lower part of the reservoir, this bottom being integral with said outlet pipe, in said reservoir a low pressure tube communicating at its lower end with said outlet pipe, a cylinder communicating at its lower end with the interior of the reservoir and with said outlet pipe and at its upper end with said low pressure tube, a piston valve arranged to slide in said cylinder and control the communication of said cylinder with the interior of said reservoir and with said outlet pipe, an auxiliary valve arranged to control the communication of said cylinder with said low pressure tube, a device for initiating the flushing operation, said cylinder and said low pressure tube being formed as two adjacent compartments in a single cast piece which is mounted on the bottom of the reservoir to constitute together with said bottom and said device for initiating the flushing operation, which is also supported by said bottom, a compact unit detachable from the reservoir.

2. Apparatus according to claim 1, wherein said device for initiating the flushing operation comprises an operating handle and a valve rod which is arranged in said low pressure tube to slide parallel with the longitudinal axis of said cylinder, said bottom of the reservoir being provided with a cast extension in which is mounted in a watertight manner the lower part of said valve rod and which supports said operating handle.

PIERRE EMILE VUAGNAT.
